UNITED STATES PATENT OFFICE.

JOHN MASON AND GEORGE W. WINSOR, OF PROVIDENCE, RHODE ISLAND,
ASSIGNORS TO THEMSELVES.

FRYING-PAN.

SPECIFICATION forming part of Letters Patent No. 310,864, dated January 13, 1885.

Application filed June 17, 1884. (No model.)

To all whom it may concern:

Be it known that we, JOHN MASON and GEORGE W. WINSOR, of Providence, in the State of Rhode Island, have invented an Improvement in Frying-Pans, of which the following is a specification.

Our invention consists in the improved double construction of the frying-pan, whereby the steam and vapors arising from the cooking materials will be drawn away and pass into the flue of the stove, as hereinafter set forth.

Figure 1 is a perspective view of our improved frying-pan. Fig. 2 is a vertical section of the same.

15 In the accompanying drawings, A represents the outer portion of the frying-pan, provided with a handle, B, for convenient manipulation, and having a circular opening, C, at its bottom, provided with an encircling 20 downwardly-turned flange, *a*, adapted to fit the kettle-hole in the top plate of a stove. The inner portion, D, is made separately from the outer portion, A, and may be provided with one or more spouts, *b*, as usual in frying- 25 pans, and the relative diameters of the portions A and D are such that when secured one within the other, as shown in the drawings, there will be left an annular space, *c*, preferably of about one-eighth of an inch in width, 30 between the parts A and D, the bottom of the parts being also similarly separated from each other, so as to form a continuous air-passage from the upper edge of the frying-pan to the kettle-hole of the stove, through which the 35 steam or gaseous products arising from the cooking materials will pass to the stove-flue.

Upon either of the parts A or D may be formed or secured the chipping-pieces *d*, which serve to hold the parts A and D at the 40 proper distance from each other, and three or

more similar pieces, *e*, may be arranged between the upwardly-turned edges *f f'* of the parts A and D, which are secured to each other by means of the rivets *g g g*, which pass through holes made in the pieces *e*, and serve to hold the two parts A and D at the proper distance from each other. The chipping-pieces *e* may be formed upon either of the parts A or D; or, instead of the fixed pieces *e*, attached to either of the parts, washers of suitable thickness encircling the rivets *g* may be employed. The outer portion, A, is made higher than the inner portion, D, and is provided with a vertical notch, *h*, adapted to receive the spout *b* of the inner portion, D, and the two parts of the frying-pan may be made either of cast-iron or sheet metal, as desired. The handle B may also be separately formed and attached to either the outer or inner portion of the frying-pan.

We are aware that it is not new to inclose a frying-pan in an outer case for the purpose of drawing the steam and vapor into the flue of the stove; but heretofore such outer case and frying-pan have been made removable from each other, and have not been adapted for use in a single utensil.

We claim as our invention—

The combination of the outer portion, A, provided with the notch *h*, with the attached inner portion, D, provided with the spout *b*, adapted to enter the notch *h*, and having a continuous air-space, *c*, between the inner and outer portions, substantially as described.

JOHN MASON.

GEORGE W. WINSOR.
